H. KOPPERS

COKE OVEN GAS MAIN VALVE

Filed Aug. 31, 1921

Inventor:
Heinrich Koppers

By: *Munsey Clark Keaywater Atty's*

UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

COKE-OVEN GAS-MAIN VALVE.

Application filed August 31, 1921. Serial No. 497,362.

To all whom it may concern:

Be it known that I, HEINRICH KOPPERS (assignor to The Koppers Development Corporation, a corporation of Pennsylvania), a citizen of Germany, residing in Essen-Ruhr, Germany, have invented a new and useful Improvement in Coke-Oven Gas-Main Valves, of which the following is a specification.

10 The invention relates to stop valves for the dry receivers of chamber ovens for producing gas and coke, and has for its principal objects to reduce the accumulation of tar on the valve and its seat, to make more 15 convenient and quick the inspection and cleaning and change of the valve and valve seat and to make the valve seat removable while it is at the same time provided with readily manipulatable means for holding it 20 tightly in place.

Particularly in connection with coal rich in tar is it impossible to avoid a soiling of the valve disc and the valve seat in the stop valves for the dry receiver of chamber ovens 25 for producing gas and coke, so that irksome cleaning work has to be carried out, since the tar becomes hard and is difficult to remove. Now, it is well known that these tar deposits 30 may be reduced by not letting the valve disc bear from above against its valve seat but on the contrary by pressing it against the valve seat from below. In this matter the valve disc and valve seat come to lie in 35 the gas space of the receiver where the valve joint surfaces are always washed about by saturated gases, so that the incrustation by tar is kept down.

By the present invention the disadvantage 40 incident to an upwardly closing valve, which consists of the necessity of taking off the entire valve box for inspecting and changing the valve disc or the valve seat, is eliminated. The solution of the problem involved in this connection is in giving such dimensions to 45 the valve seat against which the valve disc presses from below, and in fastening it to the box in so conveniently detachable a manner that it can be taken off if need be and pulled out upwardly, whereby the advantage of free accessibility and removal is afforded to the valve. While therefore, in such a valve the disc and seat are not exposed to incrustation at all or to as great an extent as in the valves pressed on their seat from

above, the exchange of valve seat and disc 55 can be carried out just as simply when occasion arises.

In the drawing an example of embodiment of the said invention is shown by a vertical section.

Referring to the drawing, on the receiver *a* usually made of wrought iron, the valve case or box *b* is placed, which is connected by a connecting piece *c* with the riser pipe *r* on top of the oven. At the bottom of the 65 case *b* the valve seat *d* is fastened by screws *e*, projecting, after the fashion of a pipe connection, into the interior of the receiver *a* and pressed against upwardly and outwardly by the valve cone *f*, which can be raised 70 and lowered with the aid of the rod *g*. The valve seat *d* is thus a ring which is loose when the screws *e* are backed out. The attachment of the seat *d* can be effected in different manners; the best way is as shown in 75 the drawing by means of obliquely placed pressure screws *e*, operable from the outside, not unlike the manner in which the valve seats are attached in pumps.

The valve rod *g* is led to the outside 80 through the lid *h* and can be tightened against its seat with the aid of the wedge *i* in the final position of the valve. Said wedge passes through a hole in the rod *g*. In order to keep the valve rod itself as free 85 from incrustation as possible in this connection, a chamber *k* is provided in the lid of the valve case for receiving oil. In order to obtain a means of cutting off the riser pipe from the receiver during the time of 90 exchanging the valve seat *d* and the valve cone *f*, a slot *l* is provided in the flange of the box *b* into which, when occasion arises a sheet metal slide *m* can be inserted.

What is claimed is—

1. A stop valve for the dry receiver in chamber ovens for producing gas and coke, with a removable lid for the valve case and the valve cone pressing outward against the valve seat, characterized by the valve seat *d* being so dimensioned and fastened that it can be conveniently withdrawn outwardly after disconnecting its attachment to the valve case and the lid *h* is removed, so as to make easy replacements possible. 100

2. A stop valve for dry receivers in chamber ovens for producing gas and coke, comprising, in combination with the casing box

- and valve-seat, a cover for the box, a valve cone pressing outwardly against its valve seat, said valve seat being adapted for removal through the casing box after the 5 cover of said box is removed, said valve seat being removably secured in place by obliquely inclined pressure screws that are adjustable from the outside of said box.
3. A stop valve for dry receivers in chamber ovens for producing gas and coke, comprising, in combination with the casing box and valve seat, a cover for the box, a valve cone pressing outwardly against its valve seat, said valve seat being adapted for removal 10 through the casing box after the cover of said box is removed, said valve seat being removably secured in place by obliquely inclined pressure screws that are adjustable from the outside of said box, and 15 a rod for moving said valve cone and an oil chamber in said box cover through which said rod extends.
4. A stop valve for dry receivers in chamber ovens for producing gas and coke, comprising, in combination with the casing box and valve seat, a cover for the box, a valve cone pressing outwardly against its valve seat, said valve seat being adapted for removal 20 through the casing box after the cover of said box is removed, said valve seat being removably secured in place by obliquely inclined pressure screws that are adjustable from the outside of said casing box, and a slot in the box casing adapted 25 to receive a sheet metal slide after the valve seat is removed in order to close the opening between the receiver and the casing box.
5. In a stop valve construction for the dry receivers of ovens, the combination of 30 a valve box having means for attachment to the receiver and oven, and having a removable top, a valve seat removably seated in said box, means operable from outside the box for tightly securing and for releasing said valve seat, a valve adapted to bear against the under side of the valve seat, and a rod connected with the valve and passing through the top of the box.
6. In a stop valve construction for the 35 dry receivers of ovens, the combination of a valve box having means for attachment to the receiver and oven and having a removable top, a valve seat removably mounted in said box and adapted to extend down
- within said receiver, means for tightly securing and releasing said valve seat, a valve adapted to bear against the lower end of the valve seat, and means for operating said valve. 55
7. In a stop valve construction for the dry receivers of ovens, the combination of a valve box having means for attachment to the receiver and oven and having a removable top provided with an oil chamber, a valve and valve seat in the lower part of 60 said box, and a valve operating rod attached to the valve and passing through said oil chamber to the outer side of said cover. 65
8. A stop valve for dry receivers in chamber ovens for producing gas and coke, comprising, in combination with the casing box and valve seat, and a cover for the box, a valve cone pressing outwardly against its valve seat, said valve seat being adapted for removal 70 through the casing box after the cover of said casing box is removed, said valve seat being removably secured in place by screws that are adjustable from the outside of said casing box, and a sheet metal 75 slide adapted to be inserted in a slot after the valve seat is removed in order to close the opening between the receiver and the casing box. 80
9. A stop valve for dry receivers in ovens for producing coke and gas, comprising, in combination: a casing; a valve seat removably secured to said casing; and a valve adapted to press outwardly against 85 said seat. 90
10. A stop valve for dry receivers in ovens for producing gas and coke, comprising, in combination: a casing; a valve seat removably secured to said casing; said valve seat adapted to extend into said receiver 95 when secured in place; and a valve cone adapted to press outwardly against said seat. 95
11. A stop valve for receivers in ovens for producing gas and coke, comprising, in combination: a casing; a valve seat removably secured within said casing, the seat portion of said valve being arranged within said receiver when secured in place; and a valve cone adapted to press outwardly 100 against said seat. 105

HEINRICH KOPPERS.
